MAGNETIC MOTION-CONTROLLING
MECHANISM

Carl Lurtz, Brooklyn, N. Y.

Application February 9, 1938, Serial No. 189,560

8 Claims. (Cl. 58—117)

This invention relates to magnetic motion-controlling mechanisms, and is, more particularly, concerned with that type of mechanism wherein the operativeness, or the specific mode of operation, of a movable operating element in the structural organization is dependent on an artificially produced magnetic field.

The invention in the present instance is embodied in an apparatus wherein the magnetically controlled operating member is adapted to control the rate of motion in a gear-train with co-operation of an escapement device, of a construction suitable for incorporation in a timing mechanism for indicating the time, or for effecting delayed action at a predetermined time in an adjunctive device operatively associated with the said escapement-controlled gear-train.

Among the objects of the present invention may be noted the provision of means for establishing in a definite region a magnetic field reactive on one or more operative members forming part of the motion-controlling mechanism characterized by a novel arrangement of its interactive parts.

In carrying out the present invention, certain novel and efficient means and mechanism are employed, among which may be mentioned the arrangement of a plurality of magnets movable one relative to the other in such a manner that the intensity of the effective magnetic field in a particular region, re-active on an operatively associated movable control-member, may be altered at will for obtaining the desired degree of magnetic operating force within specific limits.

Other features of the invention reside in the particular arrangement of the movable paramagnetic operating parts in the motion-controlling device relative to the magnets thereof, adapted to enable at least two mechanically separated movable operating parts to be interlinked for driving connection by a magnetic couple.

Features of the invention, other than those adverted to will be apparent from the hereinafter detailed description and claims, when read in conjunction with the accompanying drawing, in which:

Fig. 1 is a plan view, on line 1—1 of Fig. 2, showing the invention embodying an escapement device.

Fig. 2 is an edge view of Fig. 1, on line 2—2, showing particularly the adjustable magnet in relation to the armature of the balance-wheel shaft.

Fig. 3 is a face view of one form of a device for varying the intensity of the magnetic force effective on the armature.

Fig. 4 is an edge view of Fig. 3.

Fig. 5 is a modified form of an adjustable magnet mounting.

Fig. 6 is an edge view of a modified form of

the invention, showing adaptation of an electromagnet instead of a permanent magnet, and also a modified adjusting device for the magnet.

Fig. 7 is a face view of a horse-shoe magnet and the balance-wheel armature, in combination with which an adjustable device of a different form is shown for varying the magnetic moment.

Fig. 8 is an edge view of the magnet and armature, showing a thermostatic device for automatically moving the magnet to and fro the armature, with variation in temperature.

Fig. 9 is a cross cut of a modification, showing a magnet and armature mounted near each end of the balance-wheel arbor.

Fig. 10 is a fragmentary view of the invention, showing the magnet relative to the armature in an edge-on position.

Fig. 11 is a cross cut of another modification, showing magnets and armatures mounted respectively on two separate shafts having a common axis.

Fig. 12 is a detail view of a special construction of the balance-wheel arbor.

One form of the present invention is shown associated with a specific type of escapement, best seen in Figs. 1 and 2; this escapement may be regarded as an exemplification of the motion-controlling unit, and the several operating elements thereof will first be briefly described.

The escape-wheel 5 alternately engages with its teeth 4 the pallet 6, fixed to the lever 7; the latter is provided with a forked end 8 engaging a pin 9 which projects from the balance-wheel 10 relatively near its fulcrum. The detent 11, carried by the comparatively short arm 12, is urged by the lever 7 into the path of the oncoming escape-wheel tooth at the time the said lever 7 receives an impulse from the escape-wheel 5; thus, the latter is alternately brought to a dead stop, each time after impulse action on the lever 7 and the balance-wheel 10 ceases. Return motion of the lever 7, effected by means of the pin 9, when moving with the balance-wheel 10 in a reverse direction to that of impulsion, causes the detent 11 to move out of engagement with its escape-wheel tooth, whereupon the escape-wheel 5 is free to rotate and hence to deliver a succeeding impulse to the lever 7 which impulse in turn is transmitted to the balance-wheel 10.

The lever 7 is carried by the shaft 13, the shaft 14 carries the escape-wheel 5, and the balance-wheel 10 is fixed to the arbor 3 which is supported by frictionless bearings 15 and 16 secured respectively to the front and rear mechanism plate 17 and 18.

Two spacer posts 19 and 20 are shown in the drawings, which, together with other posts not shown, are assembled with the plates 17 and 18, which assembly constitutes the mechanism frame within which the movement is mounted, com-

prising the three journalled shafts aforein mentioned.

To the shaft 14 is mounted a small gear 21 rotating integrally with the escape-wheel 5 which is adapted to be driven by a suitable gear train, not shown, which receives its driving power from any suitable source of motive power that may be applied, such as a spring motor, a weight, or an electromagnetic machine, or some other device capable of yielding driving power for the gear train. The direction of motion imparted by the gear train to the escape-wheel 5, is shown by the arrow in Figure 1.

Having now set forth with sufficient detail the operation and construction of the particular escapement shown, it will be noted, by following the action of those escapement parts above described, that the balance-wheel 10 is impelled by the fork 7 over a relatively small arc, but once this impulse action ceases, the fork 7, in conjunction with the escape-wheel, is not adapted or capable of moving the balance-wheel back from the position to which the latter was thus thrown. At this phase of operation, as is quite evident from an inspection of the drawing, the fork 7 remains stationary, holding the escape-wheel locked with its detent 11, while the balance-wheel 10 continues to swing in the direction in which it was impelled until its force is spent. Such detached balance-wheel action is well known by those skilled in the art, the principal result achieved with this free motion of the balance-wheel is that it contributes to the maintenance of harmonious vibrations.

In the device of the present invention, the artificially created magnetic couple, indicated by reference numeral 22, effects the result heretofore accomplished by means of the hair-spring, usually adopted in time-pieces that have to work in any position.

For the purpose of the magnetic couple herein intended, the latter may be established by mounting a permanent magnet 23 so that it faces with its broad-side an armature 24 from which the stationary permanent magnet is kept at a suitable distance. Of course, in order to attain the functional characteristics of a magnetic couple as applied to an escapement, an electro-magnet may also be employed, as will be detailedly described in connection with Figure 6. Also, instead of making the armature 24 of soft iron, the armature may be made of a permanent magnet.

Considering now particularly Figures 1 and 2; there may be seen the armature 24 mounted on a split sleeve 25 wherewith it is frictionally held on the arbor 3. By virtue of said split sleeve, the armature 24 may be manually shifted lengthwise on the arbor 3 and may also be turned with comparative ease on the said arbor so as to enable the angular position of the armature 24 to be coordinated, during assembly of the device, with the angular position of the pin 9, in order to cause these members to assume a proper operative position relative to the magnetic axis of the permanent magnet 23. After assembly of the escapement parts, mounted in the mechanism frame, the armature 24, with the above consideration in view, is turned on its arbor until it causes the lever 7 to be held by the pin 9 in such a position that the escape-wheel teeth 4 clear the detent 11, while the armature comes to rest in its zero position (see Figure 1). With the escapement parts so adjusted, the device starts operating at the instant driving power is supplied to the escape-wheel 5, and no other means is

necessary to impart initial vibration to the balance-wheel, as is ordinarily the case with the conventional detached lever escapement and others.

In the device of Figures 1 and 2, the magnet 23 is shown mounted close to the inside wall of the mechanism plate 18 to which it is secured by the adjusting screw 26. The pin 21, projecting from the plate 18, passes through a hole in the magnet 23, preventing the latter from being displaced angularly but allowing the spacing between the armature 24 and the magnet 23 to be varied when the adjusting screw 26 is turned to the left or right whereby the magnet 23 is moved farther away or closer to the armature 24, thus changing the magnetic moment as required for producing the desired rate of oscillations in the armature 24. The adjusting screw 26 is provided with a neck 27 fitted into a corresponding socket in the magnet 23, as shown in Fig. 2, whereas the threaded portion of said adjusting screw passes through the mechanism plate 18 and carries on the outside thereof an indicator 28 whereby the degree of turning of the adjusting screw may easily be determined with cooperation of marks made adjacent the indicator 28 to the mechanism plate 18 or to the housing of the device, not shown in the drawing. Either the indicator 28 or the knurled knob 29 may serve to manually turn the adjusting screw.

A hole 30 is made through the midsection of the magnet 23, as shown in Figure 1, so as to clear the balance-wheel arbor 3. It will be apparent that by mounting the magnet in this manner, it can be brought very close to the armature 24, enabling a comparatively small magnet to be made effective on the armature, although there are many other arrangements which may be provided for holding the magnet at spaced relation with the armature 24. Several of such modifications are shown in various figures of the drawing which will be described in proper order.

Preferably, the center of the longitudinal section of the magnet 23 should come to lie in the center of the armature 24, which is the axis of the balance-wheel arbor 3. Such precise positioning of the magnet is of course not absolutely essential for the operation of the device, because the added friction which would be created on the farther end of the arbor 3, due to difference of magnetic moment existing on one and the other side of the armature 24, to the left and right of the arbor 3, if the magnet is not centered with the latter, is not enough to cause serious disturbances in the oscillations, provided the arbor 3 is made of a length sufficient to offset a slight athwart stress thereon in case of noncentering of the magnet 23. With a comparatively short arbor and a comparatively forceful magnetic couple, careful centering of the magnet will give improved results in time-keeping.

To effect proper interaction between the lever 7 and the impulse-pin 9 of the balance-wheel, at all times during operation of the escapement, the armature 24 and the magnet 23 are made of a shape so that the armature 24 tends to align itself, relative to the magnet 23, always in a definite angular position. In practice this result is best attained by making the armature and the magnet of elongated shape, of forms, for instance, as shown in the drawings; or of any other shape capable of establishing a magnetic couple with lines of force traversing in a definite plane so as to cause the armature 24 to swing about its own axis until its greatest length or its portion

of greatest susceptibility lies parallel to the greatest number of lines of force in the magnetic field established by means of the artificial magnet or magnets.

For the sake of economy and out of other considerations, the armature 24, being made of soft iron, is made (as shown in several figures of the drawing) much larger than the magnet 23. The latter may be fabricated from magnetite, from alloy steel of cobalt and nickel composition, or from any other alloy or substance possessing properties suitable for the production of a permanent magnet.

In preparing the magnet for the purpose herein intended, the latter, after having been charged to its maximum capacity, should be subjected to an aging process so that thereafter, when the magnet is placed in use it will not sensibly diminish in its intensity of magnetic force.

The intervening space between the armature 24 and the magnet 23 constitutes a magnetic couple which is indicated by reference numeral 22. It may be assumed that there are two couples, one at the positive and the other at the negative polar region of the magnet 23. But for the purpose of description, the intervening space between these two interacting bodies will be referred to hereinafter in the singular noun only, as the couple.

The balance-wheel 10 is prevented from being accidentally thrown over too large an arc, by the pin 31 lying in the path of the spoke of the said balance-wheel, see Figs. 1 and 2.

In the following paragraph the action of the escapement device conjointly with the magnetic couple is summed up in a few words: from the position of rest, shown in Figure 1, the escape-wheel 5 is free to turn and consequently pushes against the pallet 6, on the lever 7, transmitting an impulse to the armature 24 by medium of the forked end 88, of the said lever, and the pin 9, on the balance-wheel 10. After the impelling escape-wheel tooth clears the pallet 6, the detent 11 checks the escape-wheel 5 while the balance-wheel 10, with the armature 24, is free to swing in the direction in which it was impelled until its force of momentum is spent; the elastic magnetic couple then swings the balance-wheel 10 back, in a reverse direction, so that the balance-wheel may receive a succeeding impulse from the escape-wheel, which impulse is delivered by medium of the fork or lever 7; this cycle of operation is repeated at regular intervals as long as driving power is supplied to the escapement wheel 5.

With the armature 24 made of soft iron, the angular degree within which the balance-wheel swings in equal periods is about 180° or less. But if it is desired to effectively increase this relatively small arc of swing of the balance-wheel, up to about 300°, then the armature 24 is also made a permanent magnet of suitable material, instead of soft iron. Whereas, in this latter case, the unlike poles of the two interacting magnets attract one another, the armature 24 will place itself accordingly in a definite angular position relative to the magnet 23. If then from this zero position the armature 24 is impelled with sufficient force so that its positive pole piece moves into the region of the positive pole piece of the magnet 23, then the said armature will be moved back to its means position by medium of two characteristic forces of the twisting couple, namely, a force of repulsion and a force of attraction in the direction of

zero position of the armature 24. Assuming now that a conventional detached lever escapement is employed in association with the magnetic armature and the stationary magnet, then, the balance-wheel, owing to its force of momentum, is enabled, during its return motion, to swing to the other side of its impulse receiving position, and as the armature passes this latter position another impulse is given to it in the direction of its motion by the fork of the escapement mechanism. Thus the balance-wheel may be caused to swing over an arc as large as with the employment of a hair-spring.

Variation in the rate of oscillation of the armature may be effected by changing the magnetic moment. Many forms of devices can be constructed to accomplish this end. In the drawings are shown several different devices, incorporated with the escapement of this invention, whereby adjustment in the rate of beat can be made while the escapement is in operation.

Five different methods of changing the magnetic moment are herein disclosed, viz, first, the magnetic moment may be changed by variation in the distance of the two magnetically interacting bodies; second, by insertion of a shield; third, by blocking the magnetic field; fourth, by bridging the polar regions of the magnet, and fifth, by deflecting the effective magnetic lines of force.

Of course, in case an electro-magnet is employed, several other methods may be applied for changing the magnetic moment. For instance, any suitable device—interposed in the circuit or otherwise arranged—will serve the purpose in this instance, provided the particular device is adapted for changing the amount of electricity circulating through the coils surrounding the iron core.

One mechanical arrangement whereby the intervening space between the armature 24 and the magnet 23 can be changed, has hereinbefore already been set forth in connection with the description of the device shown in Figures 1 and 2. A similar adjusting device is shown in Figure 5. The adjusting screw 26 is here mounted with one of its ends to the midsection of the magnet 23; when the said adjusting screw is turned to the left or right in the threaded hole of the mechanism plate 18, the magnet 23 moves away or toward the armature 24 depending on the direction in which the adjusting screw is turned. The pins 32 support the magnet 23 and guide it in its motion. Said pins are fixed with their respective ends to the mechanism plate 18 and to the bracket 33; the latter is spaced from the plate 18 by short posts 34. In the bracket 33 is mounted the bearing 16 for the balance-wheel arbor 3.

It is self-evident that the bracket 33 should be made of diamagnetic material because if made of paramagnetic material it would destroy the magnetic couple almost completely. Some of the suitable metals for the bracket 33 would be brass, copper or german silver. The pins 32 are also made of nonferrous metal or dielectric material.

When the method of varying the distance between the magnet and the armature is employed for changing the degree of resiliency (the term resiliency is here adopted due to the function which the couple performs), the oscillations of the balance-wheel can be made to vary within a great range. For example if the escapement is built to deliver 240 oscillations per minute, this number of oscillations may be increased to about

400 per minute without making any changes in the escapement other than moving the magnet 23 comparatively close to the armature 24; whereas, if the said magnet is moved comparatively far away from the said armature 24, the oscillations may be decreased to about 80 per minute. In the first case the isochronism is maintained but in the second case the couple loses a certain degree of control, inducing instability in the oscillations as soon as the magnetic moment becomes too weak compared to the power of impulse imparted to the balance-wheel. This comparatively wide range of variation in the number of oscillations as above stated has been actually observed in a working model embodying the type of escapement as shown in Figure 1. In case the armature 24 is also made of permanent magnet, then still greater extremes of high and low numbers of oscillations may be achieved by vary the distance of the intervening space between the magnet 23 and the armature 24. Different maximum and minimum rates of oscillations may be attained with different types of escapements.

The fact that the escapement device of the present invention possesses this unique feature affording adjustment to be made in the rate of beat so as to cause the escape-wheel to rotate slow or fast within widely separated limits, enables one standard make of escapement to serve for the time-control of a large number of time-movements used in different industrial fields and for different purposes.

In Figures 3 and 4 is shown a form of adjusting device embodying a shield 34, adapted to be moved in or out of the space between the magnet 23 and the armature 24, for effecting a higher or lower rate of oscillations. The mechanical arrangement for moving the said shield may be of a construction different from that shown, likewise the shape of the shield and its comparative size may be greatly dissimilar from that shown without fundamentally changing its operating characteristics.

The shield 34 may be fashioned from the same material as the arm 35 from which it extends, or may be fastened to an arm made of a different material. In Figure 3 the former construction is shown. The arm 35 is limited in its downward motion by the stop pin 36, and the friction washer 37, together with the post 45, on which the arm swings, serves to hold the latter in place. On the free end of the arm 35 is provided an indicator 38, adjacent which marks 39 are provided on the mechanism plate 18, so that with cooperation of these marks the desired increase or decrease of oscillations of the balance-wheel may visually be determined.

Assuming that the shield 34 and the arms 35 are made from a thin sheet of soft iron, then a suitable ridge 40 is provided on that side of the shield facing the magnet 23, so that the former is held at spaced relation with the latter, thus not allowing an excessively large number of lines of force to be drawn off when the shield 34 is moved into the intervening space between the two magnetically interacting bodies. This ridge may be forced up from the face of the material of the shield itself or then may be made of brass or other diamagnetic material fixed to the shield.

Effects, similar to those obtained with a shield comparatively wide and spaced from the magnet, may be obtained with a shield in contact

5 with the magnet 23, provided the shield is made very thin and narrow.

For microscopic adjustment in the rate of oscillations, the shield may be made of a suitable diamagnetic material, such as copper for instance. To cause the shield made of this latter material to be effective, it should be made comparatively thick and wide, so that the entire surface, or more, of the magnet may be covered when the shield is moved in front of the latter. Only a very small number of lines of force can be drawn off by the adoption of a shield made of diamagnetic material, and the variable influence exerted on the armature 24 is correspondingly small as the shield is moved across the magnet 23, but suffices for producing a higher or lower rate of beat within small limits.

Instead of mounting the shield 34 to the outside of the plate 18, it may be mounted to the inside thereof, so that the said shield comes to lie within the armature 24 and the wall of the said mechanism plate. If the magnet shield is arranged in this manner, an outcut is made in the face of the shield, from the top down to its midsection which outcut is adapted to provide clearance for the arbor 3. A further alternative position may be given to the shield 34 by placing it to the outside of the magnet 23.

In the escapement device of Figure 4, the pin 9 is shown carried by a small disk 41, and here the weight of the armature 24 alone serves the purpose of the balance. Overthrow of the armature is prevented by the stop 42 projecting from the mechanism plate 17; this stop is provided 30 with a bend 43 lying in the path of the pin 9; the same object may be accomplished with an outcut made to the periphery of the disk 41 into which the bend 43 is made to project.

The magnet 23 is fixed to the bracket 46 in 40 any suitable manner, and the latter is held to the spacer posts 44 and 45 by the screws 47 and 48.

Partial bridging of the polar regions of the magnet 23 may be done with an iron screw or pin 49, shown in dotted lines in Figure 4. The said pin is in contact with one of its end-portions with the magnet 23, and the first named may be slid on the face of the magnet by screwing the pin 49 in or out of its supporting member 50 which is also shown in dotted lines and which is fixed above the short post 44 to the mechanism plate 18. By thus causing a smaller or greater length of the end-portion of the iron pin 49 to come in contact with the magnet 23, the magnetic moment may suitably be varied for the required adjustment in the rate of beat to be effected.

Other specific and modified construction, shown in dotted lines in connection with the device of Figure 4, will be described later in this specification.

A modification, embodying features of adjustment similar to the device last described, is shown in Figure 7. The magnet is here designated by reference numeral 51, and is made in the form of a horse-shoe. On the opposite side of the horse-shoe magnet lies the armature 52, the magnetic couple existing in the space between the said armature and the horse-shoe magnet. Lines of force are drawn off by the iron cross-bar 53 which lies on the two parallel members of the horse-shoe. By sliding the cross-bar 53 on the magnet up or down, the former is carried during its upward motion into comparatively strong polar regions, and in its downward motion

into comparatively weak polar regions; thus a gain or loss in force of the effective magnetic field between the armature and the magnet is induced by reason of the larger or smaller number of lines of force coming to lie within the cross-bar 53. As a consequence the escapement goes either slower or quicker with shifting of the cross-bar on the magnet from one position to another as above related.

The screw 54 which turns in the rigid supporting member 55, carries the cross-bar 53, the latter being held, by its bent portion 56, to the end of the said screw. All the respective members of the device shown in Figure 7 may suitably be assembled with the supporting frame of the escapement mechanism in manners similar to the other devices hereinbefore described.

For the purpose of establishing a suitable magnetic couple, interacting with the escapement device, an electro-magnet may be effectively utilized to accomplish this function.

One form of a device embodying an electro-magnet is shown in Figure 6. The application of an electro-magnet presents one particular feature which may not be attained with a permanent magnet, viz., it enables the escapement to be stopped or started from a remote distance, although the escape-wheel may still be under the influence of the driving power of the gear-train which the escapement device is adapted to control. To state more particularly; when the current for the magnet-coil 57 is cut off, then the soft iron core 58 becomes demagnetized and ineffective, as a consequence the armature 24 is not moved back to impulse-receiving position and the escape-wheel 5 (see Fig. 1) comes to rest with one of its teeth on the detent 11, while the lever 7 remains in the position it assumes after delivery of an impulse to the balance-wheel arbor 3, and in the absence of a magnetic couple no further action can take place. But at the instant the circuit is closed and current is introduced into the magnet coil 57 through the electrical conductors 59 and 60, the iron core becomes immediately magnetized, thereupon the magnetic force so produced acts on the armature 24 which now moves toward its zero position while tending to include the greatest number of lines of force; in the zero position the armature 24 is enabled to receive an impulse from the lever 7 which, during motion of the armature produced by the couple, causes the detent 11 to unlock the escape-wheel 5.

The intensity of magnetism of the iron core 58 may be controlled by a variable resistance, such as an adjustable rheostat interposed in the circuit passing through the coil 57, or instead of the last mentioned means, the magnetic moment may be changed by methods as previously described in connection with permanent magnets.

In association with the electro-magnet of Fig. 6, a modified device is shown for changing the distance between the armature 24 and the electro-magnet 58. The iron core 58 swings on a pivot 61 borne by the bracket 62 which bracket is rigid with the mechanism plate 18. To the free end of the iron core 58 is mounted a screw 63 which is held with its spherical end 64 in a corresponding socket in the plate 18. By virtue of this spherical end of the said screw, the latter is capable of moving sideways enabling the screw to adapt its position relative to the angular position of the iron core 58, which position changes relative to the screw 63 whenever manual adjustment is made.

Up to this part of the description an account has been given only of that general type of adjusting devices, for varying the magnetic moment, which were operable manually but not automatically. In the device of Figure 8 an example is given how automatic changes in the magnetic moment may be effected.

The magnet 23, facing the armature 24, is mounted on a strip of metal 65 which forms an arm for the magnet; this metal strip is provided with bent portions 67 for the accommodation of a pin 68 which passes through the bracket 69, fast on the mechanism plate 18, thus a hinge is formed for the arm 66 of the metal strip 65. To the right of the pin 68 extends a comparatively short lever 70 also formed from the said metal strip 65. The said lever is provided with a portion 71 bent at right angle to its flat side. Into the outcut 72, made to the portion 71, projects the free end of the thermostatic strip 73 which is riveted at its lower end to the mechanism plate 18.

Likewise, as in the conventional method of producing a metal strip that flexes a definite degree with a definite degree of rise or fall in temperature, the strip 73, as shown, is made of two different kinds of metals joined together. One of the metals, composing the strip 73, possesses a different heat coefficient from the other. Consequently, as the temperature changes, the end of the strip 73, projecting into the outcut 72, will move the lever 70 and the arm 66 with flexing of the strip 73, causing the magnet 23 to approach or recede from the armature 24. This automatic mechanical motion of the magnet effected due to changes in temperature may be caused to be comparatively small or comparatively large with every degree of rise and fall in temperature, depending to a certain measure on the selection of the two separate metals of the thermostatic strip 73, or the particular location of the end of the strip 73 with regard to its distance from the fulcrum of the lever 70 on which it is made to bear. With the particular arrangement of the parts as shown in Figure 8, the strip 73 moves the magnet 23 toward the armature 24, when, with flexing from rise in temperature, the free end of said thermostatic strip moves away from the plate 18; reverse motion takes place when the temperature goes down.

In case this thermostatically controlled device is applied to an apparatus in which it is desired that the oscillations of the armature accelerate with lowering of the temperature, then the strip 73 may easily be mounted so that it bends with changes in temperature, in directions contrary to those before stated. Moreover, similar reversal in the direction of motion of the magnet 23 may be effected by causing the end of the strip 73 to bear on a point of the arm 66 to the left of the pin 67.

Assuming for example that the escapement embodying the automatic thermostatic adjusting device is incorporated in a bread-toaster for the purpose of time-controlling the toasting process, then the present invention in association with this particular feature is capable of rendering a very useful function, when taking into consideration that in the process of toasting a slice of bread, if the toaster is not pre-heated, it takes a longer time period for the bread to toast a certain crispness than when the toasting process is started after the apparatus has already developed its maximum heat. With the incorporation of the hereinbefore described thermostatic time-

regulating device in a time-controlled toaster, the length of time adapted for toasting the bread a certain crispness, with a given heat output of the apparatus, would automatically be shortened or lengthened by the difference of speed of the timing mechanism, effected by changes of temperature in the toaster.

Similarly, the thermostatic time regulating device may be adapted to an escapement used in clocks for compensation of the balance, when the latter expands or contracts due to changes in temperature. In case of this latter application, the thermostatic device is so constructed that it effects changes in the magnetic moment of suitably small degrees.

The magnet shield 34 of the device of Figure 3, or the cross-bar 53 of the device of Figure 7, may equally well be adapted to be automatically operated by an element such as a thermostatic strip, or a thermostatic device of different construction capable of rendering the function of the one device herein disclosed.

An arrangement of magnet and armature, different in certain respects from the arrangement of these parts heretofore described, is shown in Figure 9. Here two armatures, indicated by reference numeral 74, are shown mounted to the arbor 3; one of said armatures faces the front plate 17 and the other faces the rear plate 18. Also, two magnets are employed; the magnet 75 is secured in an outcut in the plate 17, the former also serving as a bearing for the arbor 3. The other magnet 76 is similarly arranged, being accommodated in an outcut of the plate 18 in which the magnet may be moved in or out with cooperation of the bracket 77 and the adjusting screws 78 so that the distance between the two magnets, serving in this instant also as bearings, may be properly adjusted for the necessary play of the arbor 3.

It is to be noted, that once the two magnets are set in place they are not adjusted any more for the purpose of changing the distance of the intervening space between the magnets and their respective armatures. In this device the armatures are adapted to be moved for the purpose of changing the rate of oscillations. In view of this fact, the armatures are mounted loosely on the arbor 3 on which they may be slid in a lengthwise direction of the arbor by adjusting screws 79, thus affording the couple to be made weaker or stronger. Near each of the two armatures 74 is frictionally held, to the arbor 3, a support 80 into which the said screws 79 are fitted; turning of these screws changes the dimension of the couple, hence changing the number of vibrations in a measured time period.

Midway of the arbor 3 is shown a disk 41 with its pin 9 which is adapted to cooperate with a lever, or directly with an escapement wheel, for alternate impulses to be delivered to the arbor 3, maintaining the operation of the escapement with the aid of the magnetic couple. In connection with this last described device it is feasible to change the magnetic moment by means of the shielding or bridging method, in which case the screws 78 and the supports 80 could be dispensed with, the armatures being then rigidly mounted to the arbor 3.

When use is made of two pairs of magnetically interacting bodies, mounted on one shaft as shown in Figure 9, it enables the magnets to be made of comparatively small size. An important advantage is further provided by this arrangement in that it prevents any possible change of

magnetic moment to occur if the arbor 3 is slightly displaced longitudinally due to play in the bearings. Such displacement of the said shaft may of course take place only when the timing device works in one particular position, namely face down, which normally is the side of the plate 17. In the most common positions in which time pieces are placed when working, an escapement device operating with only one magnet will not be disturbed by play in the bearings of the arbor 3, because in any other position except face down, the armature with its arbor will be drawn towards that one magnet.

To avoid undue multiplications of drawings a further modification of a particular arrangement of magnets, cooperative with a vibrating armature, is shown in dotted lines in Figure 4, between the two mechanism plates 17 and 18. It is to be kept in mind that the fundamental function of the magnetic force as applied in this invention may be accomplished by means of several separated magnets of comparatively small size instead of one magnet of comparatively large size. The two small magnets 81, seen in Figure 4, are held at a suitable distance from the face of the armature 24, by the supporting member 82 which is shown in the form of a rod fixed with its respective ends to the spacer posts 19 and 20. But any other suitable means may be employed if desired for supporting said magnets. The mean position which the elongated part of the armature assumes, when exposed to the magnetic field of these two magnets, is the axis, more or less, traceable through the two magnets 81. A singular characteristic which this particular arrangement of two magnets presents is that the rate of oscillations of the armature 24 may be changed by shifting the magnets 81 toward the center of swing of the armature 24 or away from the center of swing. These stated results, due to shifting of the two magnets from one position to another, are derived from obvious reasons, namely, when the two magnets lie relatively close to the axis of the arbor 3, the leverage, so to speak, of the magnetic force acting on the armature 24 is comparatively small, whereas the reverse is the case when the two magnets 81 are moved, on their supporting member 82, to a position relatively far from the fulcrum of the armature 24. The effect which the magnetic force of the two separate magnets 81 has on the armature 24 is comparable with the effect of two separate very flexible springs, which may be imagined each one connected with one of its ends to the supporting rod 82 and with the other end connected to the armature 24, pulling thereon when the latter is moved away from its zero position. It may therefore be readily seen that the action of magnetic force of two magnets arranged as immediately above described, is, in certain respects, different than the action of a single magnet placed broad-side on centrally of the armature 24.

Another pair of magnets may be employed in practice, this second pair of magnets to be mounted in a similar manner as the magnets 81, but on the opposite side of the armature 24, thus the lengthwise displacement of the arbor 3 will not induce any changes in the rate of oscillations of the armature 24.

A description now follows of two distinct and separate device whereby the magnetic moment may be changed by the deflection method or blocking method, respectively. The device of the deflection method will first be considered.

Reference may be had to Figure 4 where this particular device is shown on the outside of the bracket 46.

In rear of the magnet 23 is placed another magnet 83 which is held frictionally to the bracket 46 in any suitable manner so that the magnet may be manually turned clockwise or counter-clockwise. The stem 84, shown broken away, serves as a manipulating member.

Applicant is not aware that heretofore the magnetic effect produced by two magnets, similarly arranged, has been applied in practice in connection with any device whatsoever. For this reason, the magnetic effect manifested by two permanent magnets close together, as experimentally established, will be set forth in the following paragraph.

When the magnet 83 lies in a position so that its negative and positive polar regions face the opposite polar regions of the magnet 23, lines of magnetic force are drawn off by the magnet 83, and a corresponding slowing down in the oscillations of the armature 24 results; whereas when the magnet 83 is turned away from that position, the rate of oscillations of the armature 24 increases and reaches a maximum increase when the magnet 83 is brought to a position with its two polar regions facing like polar regions of the magnet 23. This maximum number of oscillations, so produced by means of the magnet 83, is considerably higher than the number of oscillations produced with one single magnet of a volume equal to both the volume of the magnet 23 and the magnet 83 together. It may therefore be assumed that in the position of repulsion of the two magnets, magnetic lines of force are deflected by the magnet 83 to the other side of the magnet 23, at which side the armature 24 is located. The above stated magnetic effect was observed with the magnet 83 smaller in size than the magnet 23. If the magnet 83 is made larger than the magnet 23 then the former overpowers the latter, causing the polarity of the magnet 24 to be ineffective on the armature 23 and the armature tends to move to a zero position determined by the larger magnet. The magnet 83 should therefore be made smaller than the magnet 23 in order to preserve the function of the latter for which it is here assigned.

It is felt that no drawing is considered necessary for the disclosure of a device for changing the magnetic moment by the blocking method. In its simplest form this device consists of a piece of soft iron mounted on an adjustable arm in the vicinity of the magnet 23. The adjusting arm may be provided with a screw whereby the free end of the arm with its iron piece may be moved closer to or farther away from the magnet 23, as a result more lines or fewer lines of force are drawn off by the iron piece on the arm in the vicinity of the magnet 23.

In Figure 10 is illustrated still another form of magnet interacting with a vibrating armature. The magnet 85, shown U-shaped, is in this device so positioned relative to the armature 24 that the magnetic effect of the edge-on method is brought to bear on the oscillating armature. The magnet 85 is mounted on an adjustable rod 86 by means of which the former may be moved inwards or outwards of the rim of the armature 24, thus enabling time adjustment to be made. The armature 24 swings with a portion of its elongated section within the parallel bars of the magnet 85. In practice a second magnet may be placed similarly on the

opposite side of the one shown in order to prevent the armature 24 from being pulled toward one side.

More than two magnets may also be effectively employed, and if, for instance, four magnets are employed then the armature 24 is made in the form of a cross, or some similar shape, having the end-portion of each arm project into the U-shaped magnet 85, as is illustrated in Figure 10.

10 The modification shown in Figure 11 possesses certain features and advantages which are not embodied in any of the above described devices. It will be noted that there are two shafts 87A and 87B so mounted that they are jointly oscillant on a common axis, although they are not interlinked by any mechanical means. The shaft 87A lies between the mechanism plate 17 and 18, while the shaft 87B is mounted between the plate 18 and the bracket 88. The bearing 16B is fixed in the plate 18 and is provided with conical depressions, one on either side of the plate 18, thus providing the bearing sockets for one end of each shaft 87A and 87B. The other ends of the said shafts are journaled respectively in the plate 17 and the bracket 88.

15 To the shaft 87A is rigidly mounted a permanent magnet 89; likewise, a permanent magnet 90 is mounted to the shaft 87B so that a couple 91 is established between these said two magnets. Between the magnet 90 and the bracket 88 another magnetic couple 92 is established by making said bracket 88 of soft iron or other suitable paramagnetic material. Both permanent magnets are made of an elongated shape and are so adjusted on their respective shafts, relative to the bracket 88, that when the said magnets assume their mean position, which is the magnetic axis common to said three interacting bodies,

20 25 30 35 40 45

An escapement device such as shown in Figure 1, or any other suitable type of escapement may be cooperatively adapted for alternately impelling the shaft 87A.

50 55 60 65 70 75

By reason of the mutual attraction of the magnet 89 and the magnet 90, a greater magnetic moment is developed in the intervening space between these two magnets than in the intervening space between the magnet 90 and the bracket 88, although the spacing of these separate intervening spaces may be equal or nearly so. As a result of this difference in magnetic moment a difference of elasticity of the two couples 91 and 92 is achieved. This object of course may be attained with only one permanent magnet, when substituting a soft iron piece for the magnet 89. In this latter case, the magnet 90 is moved closer to the said iron piece, and the intervening space between the magnet 90 and the iron bracket 88 is made correspondingly wider.

To present the characteristics manifested by the three magnetically interacting bodies more clearly to the mind, it may be imagined, for instance, that a spiral spring is connected with one end to the magnet 89 and with its other end to the magnet 90; likewise, another spiral spring to be connected with one end to the magnet 90 and with the other end to the bracket 88.

70 75 Now, the main purpose of providing a weaker magnetic field for the couple 92 than for the couple 91, is to cause the shaft 87B to turn with the shaft 87A when the latter is mechanically impelled, and, further, to enable the shaft

87B to overcome its initial resistance to turning with greater ease, which resistance is introduced by reason of the magnetic axis of the couple 92. The functional characteristic of the couple 91 is mainly that it compensates for inequalities of impulses received by the pin 9, which inequalities of impulses are liable to occur due to variation in the driving power of the escape-wheel, which may be incorporated with this device.

A further illustration of the action of the component parts of the device of Figure 11, is set forth in this paragraph. When the impulse, delivered to the shaft 87A, is comparatively strong, the magnet 89 lags in its angular motion, following the magnet 88, more than when the impulse is comparatively weak. By virtue of this action a much heavier balance may be operated with a comparatively weak impelling force of the escapement, because the twisting power in the couple 91 may be gradually increased, thus enabling effective force to be built up gradually to a degree sufficient for overcoming the inertia of the loaded shaft 87B. Another advantageous feature of this device is that when the shaft 87A is suddenly stopped in its rotation, the shaft 87B may continue in its rotation in the same direction beyond that of the shaft 87A, and after the shaft 87B comes to a stop it is moved in a reverse direction by medium of the twisting force of the couple 91. As soon as the stress on the shaft 87A is relieved by return of the shaft 87B, both shafts are then enabled to again swing together in the direction last named.

As shown in the drawing, the shaft 87B carries two arms 93 to which slidable weights 94 are mounted, thus providing the means for the force of momentum suitable for a definite rate of oscillation of the shaft 87A and 87B. Instead of weights, air-engaging vanes 95 may be mounted on the free ends of the arms 93, respectively; these air-engaging vanes are shown in dotted lines in the drawing.

If the pin 9 is substituted by a pallet of a construction similar to the construction of the pallet shown on the balance-wheel arbor of the escapement device disclosed in my application, Serial Number 70,773; filed March 25, 1936, then the device of Figure 10, of this application, may effectively be adapted to operate in combination with a lever and escape-wheel as disclosed in the prior application. However, other forms of escapements operating on the recoil principle, or on other principles, may also be adapted for operation in conjunction with the last described device, illustrated in Figure 11.

A balance-wheel shaft of special construction is shown in Figure 12. By reason of this particular shaft-construction it is possible to make the greater portion of the body of the shaft of diamagnetic material, for instance such as phosphor bronze, german silver, brass, or non-metallic material; thus no appreciable magnetic flux is able to pass into the main body of the shaft which is adapted to carry the magnet, the armature, the balance-wheel, or other load.

As may be clearly seen in the drawing, the shaft 3B is provided at its lower end with a pivot 96, the latter is shown being formed from the diamagnetic material of the shaft 3B, which pivot is adapted for the reception of a conical tip 97 which forms the bearing portion of the shaft. This shaft-tip 97 can be economically made, due to its comparatively small size, from high grade

hardened steel which will stand wear for a comparatively long time; whereas the larger portion of the entire shaft, being made of a softer material, can be easily and economically machined.

5 Furthermore, if the shaft-tip 97 wears down during long and continued operation, it is a simple task to remove the worn shaft-tip from the supporting pivot 96 and to substitute a new tip therefor. Both ends of the shaft may be 10 constructed in this fashion, or another construction may be adopted such as is shown at the upper end of the shaft 3B in the same drawing-figure. At this end, the shaft 3B is provided with a bore 98 into which is fitted a small disk 99 which 15 may be made of suitable hard steel. A hole 100 is made into the said small disk to accommodate a pin 101; the latter abuts the bottom of the bore 98, preventing the flat end of the shaft to come in contact with the shoulder of the screw 102. 20 In order to enable the pin 101 to be properly adjusted relative to the shaft 3B, the former is fashioned from the end-portion of the screw 102 which is screwed into the mechanism plate to an extent allowing sufficient play between the end 25 of the pin 101 and the bottom of the bore 98, while the other end of the shaft rests in its bearing. In case the bearing for the other end of the shaft 3B is made so as to be adjustable, then the pin 101 need not have a threaded portion, and 30 the former may be fixed to the mechanism plate in any other suitable manner. Into the cavity, provided by said bore 98, oil may be put to reduce friction. As there is no other opening for the bore 98 except the one through which the pin 35 101 passes, the oil cannot flow away and will therefore provide lubrication for a very long time. Moreover, there is no chance for dust to mix with the oil whose lubricating quality will therefore be preserved over a great extent of time during operation of the device. When the hole in the small disk 99 is worn out, a new disk may be substituted.

The escapement of the present invention—which is constructed substantially so that an artificially produced magnetic couple affords the control in the rate of beat of the balance-wheel arbor and other members connected therewith—may also be adapted to perform this function in connection with an electric time-control system comprising a primary clock (also called a master clock) and secondary clocks; the master clock being so constructed as to produce a fluctuating current in the circuit at regular intervals by means of which current the secondary clocks are operated.

Having now particularly described and ascertained the nature of my invention, I would state in conclusion that, while the illustrated examples constitute practical embodiments of my invention, I do not desire to be restricted to the details of construction and arrangement of parts of the various constructions illustrated in the accompanying drawing, since manifestly they can be considerably varied without departure from the spirit of the invention.

I claim:

1. In combination, a first journalled shaft, a second journalled shaft having a common axis with the first shaft but mechanically separated therefrom, means to actuate one of said shafts, paramagnetic substance carried by the first shaft, paramagnetic substance carried by the second shaft, and a stationary paramagnetic substance disposed in the vicinity of the paramagnetic substance of the second shaft, one or more of said

paramagnetic substances being permanently magnetized to create magnetic couples in the intervening space between the paramagnetic substances, one couple being adapted to effect motion in the second shaft when the first shaft is actuated, and the second magnetic couple being adapted to impede the motion of the second shaft when the latter is displaced angularly relative to the magnetic axis of the stationary paramagnetic substance.

2. The combination with a time-governing device, comprising a shaft and a paramagnetic balance on said shaft, positive means for impelling said balance in an angular direction, and a first and second magnet disposed in proximity of the balance to produce magnetic couples whereby a counteractive force is set up when the balance is impelled over a definite angular degree; said first magnet being disposed broadside-on at one side of the balance, and the second magnet being disposed broadside-on at the opposite side of the balance to enable the latter to move closer to the magnet at one side when the balance recedes from the magnet at the other side to effect power compensation in the interacting magnetic couples of said first and second magnet.

3. In combination, an armature adapted to perform a mechanical operation, a first magnet disposed in proximity of the armature for producing a magnetic couple between the armature and said magnet on which couple the performance of operation of the armature depends; a second magnet disposed in proximity of the first magnet; the first magnet lying intermediate of the armature and the second magnet; the second magnet possessing a weaker magnetic moment than the first magnet, and means for moving the second magnet at will into a stationary position of magnetic repulsion or attraction relative to the first magnet to cause a greater number of lines of force to become disposed in said couple when the said two magnets are in a position of repulsion relative one to another as compared to the number of magnetic lines of force becoming disposed in said couple when the first and second magnet are in a position of magnetic attraction relative one to another.

4. In combination, an armature adapted to perform a mechanical operation, a first magnet disposed in proximity of the armature for producing a magnetic couple between the armature and said magnet on which couple the performance of operation of the armature depends; a second magnet disposed in proximity of the first magnet, and means for moving the second magnet at will into a stationary position of magnetic repulsion or attraction relative to the first magnet to cause a greater number of lines of force to become disposed in said couple when the said two magnets are in a position of repulsion relative one to another as compared to the number of magnetic lines of force becoming disposed in said couple when the first and second magnet are in a position of magnetic attraction relative one to another.

5. In combination, a first pivoted vibratory member adapted to be impelled periodically over a limited angular degree away from its mean angular position, a second co-acting oscillatory member mechanically separated from the first member; paramagnetic substance carried by the first vibratory member, paramagnetic substance carried by the second co-acting oscillatory member; the said substance of at least one of said members being permanently magnetized for the 78

production of a magnetic couple whereby an operative link is established between the first and the second member to enable both to swing reciprocally in harmony, and supplementary means adapted for imparting retro-active force to the second oscillatory member when away from its normal angular position to afford co-active impulse action to be effected periodically in the first and second member.

- 10 6. A magneto-kinetic device having a supporting frame, a movable mass in said frame having an effective magnetic field adapted to determine the position of the mass relative to its support, means co-active with the mass, said means being 15 adapted for the production of a useful function dependent on the action of the mass subject to the effect of the magnetic field, a plurality of magnets interactively arranged in the vicinity of the effective magnetic field for establishing its 20 intensity, said plurality of magnets comprising a minimum of two in number disposed in proximity relative one to another to enable the normal range of certain lines of force of the magnets to be modified, and means for at will altering the 25 position of one magnet relative to the other to any degree of magnetic attraction or repulsion in relationship with respect to each other for selectively establishing a lesser or greater degree of force of magnetic moment in said effective magnetic field reactive on the movable mass.
- 30 7. In a magneto-kinetic device, a support, an angularly movable paramagnetic mass having a magnetic field, means magnetically coupled to said mass for the performance of a useful function, a first magnet arranged for supplementing the magnetic force of the field reactive on the paramagnetic mass, said first magnet having its magnetic axis disposed in a definite direction relative to the mass to enable the latter to assume 40 a normal angular position; a second magnet having a weaker magnetic moment as compared to the magnetic moment of the first magnet to enable the latter to retain the predominant influence in the establishment of the magnetic axis 45 in a definite direction; the second magnet being disposed in proximity of the first magnet at one side thereof for modifying the effectiveness of the magnetic field acting on the paramagnetic mass, and means for at will altering the position of the 50 second magnet relative to the first magnet in a manner to enable the said two magnets to occupy relative to one another a position of magnetic repulsion or attraction or a position anywhere intermediate of the two first stated relative positions for selectively altering the effectiveness of the magnetic field in which the paramagnetic mass is adapted to operate.
- 55 8. In a magneto-kinetic device, a paramagnetic mass having a magnetic field, the mass being adapted to move within certain limits from one position to another, means magnetically coupled to said mass for the performance of a useful function, a first magnet in the device adapted for the establishment of a definite magnetic moment in the magnetic field whereby the action of the said mass is influenced, a second magnet disposed in a definite position relative to the first magnet for modifying the intensity of magnetic force of the latter, and an instrumentality for disposing the second magnet stationarily in a definite selected position of magnetic repulsion relative to the first magnet for causing a definite amount of magnetic force of said first magnet to be deflected into the magnetic field in which the said mass is operative.

CARL LURTZ.
